UNITED STATES PATENT OFFICE.

EMANUEL J. BOYLER, OF PETERBOROUGH, ONTARIO, CANADA, ASSIGNOR OF TWO-THIRDS
TO COURTLAND JOHN AGGETT AND ANGUS STALKER, OF PETERBOROUGH, CANADA.

EXPLOSIVE-ENGINE.

No. 880,503.

Specification of Letters Patent.

Patented March 3, 1908.

Application filed June 1, 1906. Serial No. 319,759.

To all whom it may concern:

Be it known that I, EMANUEL JOHN BOYLER, of the city of Peterborough, in the county of Peterborough and Province of Ontario, Canada, have invented certain new and useful Improvements in Explosive-Engines; and I hereby declare that the following is a full, clear, and exact description of the same.

This invention relates to an explosive engine in which the gas is admitted to the bore of the engine cylinder alternately on opposite sides of the piston head, and then exploded to drive the piston head alternately towards the opposite ends of the engine cylinder, as hereinafter described and specifically pointed out in the appended claims.

In the drawings: Figure 1 is a side elevation of an explosive engine. Fig. 2 is a vertical section through the explosive engine on a larger scale than in Fig. 1. Fig. 3 is a horizontal section taken centrally through the engine cylinder.

Like characters of reference refer to like parts throughout the specification and drawings.

The ends of the engine cylinder *a* are closed by the cylinder heads *b* and *c* and movable within the bore of the engine cylinder *a* between the cylinder heads *b* and *c* is the piston head *d*. Centrally connected to the piston head *d* is the piston rod *e* which projects through a centrally located bore *f* in the cylinder head *c* and through the packing box protecting the engine cylinder from gas leakage through the bore *f*. Fixed on the piston rod *e* on the outer side of the cylinder head *c* is a cross head *h* having guide rods *i* slidable through guideways *j* attached to or forming part of the cylinder casing and located at the sides of the outer surface thereof. Journaled in bearing boxes *k* adjacent to the cylinder head *b* is the engine shaft *l* provided with cranks *m* and connected to the cross head *h* and to the cranks *m* are crank rods *o*. Mounted upon the engine shaft *l* between the crank *m* are balance wheels *p*. Formed through the casing of the engine cylinder *a* adjacent to the cylinder heads *b* and *c* are screw threaded bores *q* and *r*, and fitted to the screw threaded bores *q* and *r* are the inner ends of the mixing chambers *s* and *t* of the carburetors. The mixing chambers *s* and *t* are pro-

vided with injectors *u* and *v*, each comprising a fuel chamber *w* a fuel inlet *x* for the fuel chamber connected with the fuel supply and a fuel outlet *y* connected with the fuel inlet and its respective mixing chamber. The injectors *u* and *v* are provided with slideways *a'* and *b'* communicating with the fuel chambers *w*, and movable in the slideways *a'* and *b'* are suckers *c'* and *c''* coupled together by a link *d'*. Projecting from the link *d'* is a pin *e'* longitudinally movable in a slideway *f'*, and actuating the pin *e'* is an eccentric rod *g'* provided with an eccentric strap *h'* which encircles the eccentric *i'* mounted upon the engine shaft *l*. During the revolution of the engine shaft *l*, the eccentric *i'* actuates the eccentric rod *g'* to cause the reciprocation of the link *d'* and the actuation of the suckers *c'* and *c''*. At the ends of the engine cylinder *a* are exhaust ports *j'* and *k'* closed by interiorly opening valves *l'* and *m'*. The valves *l'* and *m'* are connected with the piston head *d* by connecting means *o'* and *p'*. The exhaust ports *j'* and *k'* discharge into the muffler *q'*.

In the operation of the engine, gas is admitted from the mixing chamber *s* into the engine cylinder on the side of the piston head *d* adjacent to the cylinder head *b* and when exploded by the igniter *m''* moves the piston head *d* towards the cylinder head *c*. As the piston head *d* approaches the cylinder head *c* it actuates the connecting means *o'* to open the valve *l'* and permit of the escape of the exploded gas through the exhaust port *j'*. When the piston head *d* has completed its stroke towards the cylinder head *c* and commenced its return towards the cylinder head *b* it forces the exploded gas through the exhaust port *j'* and when the piston head *d* has completed its return stroke towards the cylinder head *b* it moves the valve *l'* to close the exhaust port *j'*. When the piston head *d* has completed its stroke towards the cylinder head *c* and is about to commence its return stroke towards the cylinder head *b*, the eccentric *i'* actuates the eccentric rod *g'* to move the sucker *c''* and eject a selected quantity of fuel from the fuel chamber *w* of the injector *v* into the mixing chamber *t*. When the piston head has passed the dotted line *d''* on its return stroke towards the cyl-

inder head *b* it creates a partial vacuum in the engine cylinder on that side of it adjacent to the cylinder head *c*, and the pressure of the gas within the mixing chamber *t* then 5 opens the valve *e* controlling the gas outlet of the mixing chamber *t* and enters the engine cylinder between the piston head *d* and cylinder head *c*. When the piston head *d* has passed the dotted line *d*', the gas within 10 the engine cylinder is exploded and the piston head *d* is forced to the end of its stroke in the direction of the cylinder head *b*. When the piston head *d* has completed its stroke in the direction of the cylinder head *b*, it opens 15 the valve *m* controlling the exhaust port *k*' so that during its return stroke towards the cylinder head *c* it will exhaust the exploded gas through the exhaust port *k*'.

As the piston head *d* completes its stroke 20 towards the cylinder head *c* it moves the valve *m*' to close the port *k*' to retain in the engine cylinder the next charge of gas from the mixing chamber *t*. As the piston head approaches the cylinder head *b*, the eccentric 25 *i*' actuates the eccentric rod *g*' to move the sucker *c* of the injector *u* to eject a selected quantity of fuel from the fuel chamber *w* into the mixing chamber *s*. When the piston head *d* has completed its stroke in the 30 direction of the cylinder head *b* and has returned to the dotted line *f*}', it creates a partial vacuum within the engine cylinder between itself and the cylinder head *b* so that the pressure of the gas within the mixing 35 chamber *s* will automatically open the valve *g*'' controlling the gas outlet from the mixing chamber *s* into the engine cylinder. When the piston head *d* has passed the dotted line *f*'' as it moves towards the cylinder head *c* 40 the gas within the engine cylinder is exploded by the igniter *o*'' and the piston head is driven by the result of the explosion in the direction of the cylinder head *c*.

As shown in the drawings, the engine shaft 45 *l* is located at one end of the engine cylinder, and the cross head *h* for the piston rod is located at the opposite end with the crank rods *o* connecting the cranks *m* of the engine shaft with the cross head at the sides of the 50 engine cylinder. By means of this construction, the engine can be confined in a space equal to the length of the engine cylinder plus the fly wheels and the length of the stroke of the piston cross head.

Having thus fully described my invention 55 what I claim as new and desire to secure by Letters Patent is:

1. An explosive engine comprising an engine cylinder, cylinder heads at the ends 60 thereof, a piston movable within the engine cylinder between the cylinder heads, mixing chambers fitted to the engine cylinder adjacent to the cylinder heads and on opposite

sides of the piston, fuel injectors for the mixing chambers, suckers for the fuel injectors, means coupling the suckers together and means for actuating the suckers. 65

2. An explosive engine comprising an engine cylinder, cylinder heads at the ends thereof, a piston movable within the engine cylinder between the cylinder heads, a piston rod for the piston projecting through one of the cylinder heads, a cross head for the piston rod, an engine shaft, cranks for the engine shaft, crank rods connecting the engine shaft cranks with the cross head, mixing chambers fitted to the engine cylinder adjacent to the cylinder heads and on opposite sides of the piston, fuel injectors for the mixing chambers, suckers for the fuel injectors, means coupling the suckers together, and means for actuating the suckers. 70 75 80

3. An explosive engine comprising an engine cylinder, cylinder heads at the ends thereof, a piston movable within the engine cylinder between the cylinder heads, a piston rod for the piston projecting through one of the cylinder heads, a cross head for the piston rod, guide rods for the cross head, guideways for the guide rods, an engine shaft, 85 cranks for the engine shaft, crank rods connecting the engine shaft cranks with the cross head, mixing chambers fitted to the engine cylinder adjacent to the cylinder heads and on opposite sides of the piston, fuel injectors for the mixing chambers, suckers for the fuel injectors, means coupling the suckers together, and means for actuating the suckers. 90 95

4. An explosive engine comprising an engine cylinder, cylinder heads at the ends thereof, a piston movable within the engine cylinder between the cylinder heads, a piston rod for the piston projecting through one of the cylinder heads, a cross head for the piston rod, an engine shaft, cranks for the engine shaft, crank rods connecting the engine shaft cranks with the cross head, mixing chambers fitted to the engine cylinder adjacent to the cylinder heads and on opposite sides of the piston, fuel injectors for the mixing chambers, fuel chambers for the fuel injectors, pump chambers for the fuel chambers, plungers in the pump chambers, means coupling the plungers together, and means imparting a reciprocating movement to the 100 105 110 115 plungers.

5. An explosive engine comprising an engine cylinder, cylinder heads at the ends thereof, a piston movable within the engine cylinder between the cylinder heads, a piston rod for the piston projecting through one of the cylinder heads, a cross head for the piston rod, an engine shaft, cranks for the engine shaft, crank rods connecting the engine shaft cranks with the cross head, two mixing 120 125 chambers fitted to the engine cylinder adj-

cent to the cylinder heads, one on each side of the piston, fuel injectors for the mixing chambers, fuel chambers for the fuel injectors, alined pump chambers for the fuel chambers extending therefrom towards one another, plungers in said pump chambers connected at their outer ends, and means for im-

parting a reciprocating movement to the plungers.

Toronto, May 7th A. D. 1906.
